UNITED STATES PATENT OFFICE

162,710

BOX

Bernard C. Brazeau, Wisconsin Rapids, Wis., assignor to Cranberry Growers, Inc., Wisconsin Rapids, Wis., a corporation of Wisconsin

Application September 17, 1949, Serial No. 5,055

Term of patent 14 years

(Cl. D58—12.6)

To all whom it may concern:

Be it known that I, Bernard C. Brazeau, a citizen of the United States, residing at Wisconsin Rapids, in the county of Wood and State of Wisconsin, have invented a new, original, and ornamental Design for a Box, of which the following is a specification, reference being had to the accompanying drawing, forming part thereof.

Fig. 1 is a view in perspective of a box embodying my new design.

Fig. 2 is a view in cross section through the box shown in Fig. 1.

The dominant feature of my design resides in the specific shape of the cut-out window in the box top as shown in the drawing.

I claim:

The ornamental design for a box, as shown and described.

BERNARD C. BRAZEAU.
